UNITED STATES PATENT OFFICE.

BENJAMIN A. PILLOW, OF RICHMOND, VIRGINIA.

BOOT OR SHOE.

SPECIFICATION forming part of Letters Patent No. 367,118, dated July 26, 1887.

Application filed February 28, 1887. Serial No. 229,229. (No model.)

To all whom it may concern:

Be it known that I, BENJAMIN ALLEN PILLOW, a citizen of the United States, residing at Richmond, in the county of Henrico and State 5 of Virginia, have invented certain new and useful Improvements in Boots and Shoes; and I do hereby declare the following to be a full, clear, and exact description of the invention, such as will enable others skilled in the art to which 10 it appertains to make and use the same.

My invention is an improvement in boots or shoes; and my said invention consists in certain details of construction and arrangement of the parts composing the same, as and for the purposes as will be hereinafter more 15 fully described, and form the subject-matter of the claims.

The object of this invention is to form a water-tight boot or shoe that will be serviceable, and, by conforming to the peculiar 20 outlines of the foot, be comfortable to the wearer.

For a better understanding of the details of construction of a boot or shoe when constructed according to my invention, reference is had to 25 the accompanying drawings, in which—

Figure 1 represents a bottom view of the pattern as cut from a piece of sole-leather to form the combined sole, welt, and counter. Figs. 2 and 3 are transverse sections on the lines *w w* 30 and *xx*, respectively, of Fig. 1. Fig. 4 is a plan view, and Fig. 7 a side elevation, of the combined sole, welt, and counter as formed from the pattern shown in Fig. 1. Figs. 5 and 6 are transverse sections on the lines *y y* and *z z*, respectively, of Fig. 4. Fig. 8 represents a transverse section of a lasted upper; and Fig. 9 a similar view showing the ends of the upper as turned up preparatory to applying the combined sole, welt, and counter shown in 35 Figs. 4 and 7. Figs. 10 and 11 represent a vertical transverse and a vertical longitudinal sectional elevation of a boot or shoe as formed according to my invention, the same being formed with a double sole. Fig. 12 is an elevation, partly in section, of a single-sole boot or shoe. Fig. 13 is an enlarged detail of a portion of the edge of a boot or shoe, showing the manner of uniting the upper to the combined welt, sole, &c.

50 In carrying out my invention I proceed as follows: From a suitable piece of sole-leather the pattern A A' (represented in Fig. 1) is first cut, having the general outline of the foot. From the heel portion A' of this pattern are now cut the four V-pieces, 1 2 3 4, which leave 55 the three radially-projecting pieces, *a b c*, whose edges are now beveled, as shown at *a' b' c'*, as also the edges of the adjacent part A², which are beveled to correspond, as shown at *a'*, whereby, when bent up into position to form the counter of the boot or shoe, these pieces *a b c* and A² will lap one upon the other, as shown in Fig. 4. Commencing, now, just forward of the heel part A', a cut or kerf is made into the leather, not quite midway of its thickness, as 60 shown at *d*, Fig. 2, and about half an inch deep, and extending all around the foot portion of the pattern and about half an inch from its outer edge, as shown in Fig. 1. The result of this is that the edge of the foot portion of the 65 pattern is divided into two parts, as shown at *e* and *f*, Fig. 2. After this slit is made in the pattern the edges thereof, as well as the outer edges of the heel portion, are beveled or tapered, as shown at *g*, Fig. 2, in order to decrease 70 the thickness of the part *e* and pieces *a b c*, and A² at their outer edge, whereby a neat and smooth union is the result between these parts and the upper when said upper is applied thereto, as will presently appear. The pattern is now finished; and the next step is to 75 form or shape the same into the desired outline, and to accomplish which I proceed as follows: The pattern is first soaked in water or otherwise softened, after which it is placed 80 upon a last corresponding to the foot of the person upon whom the finished boot or shoe is to be worn, with the surface of the pattern represented in Fig. 1 down and the plane surface against the last. The edges *e* of the 85 foot part and pieces A² *a b c* of the heel are now pressed and worked up and over upon the last, where, as the proper position is reached, it is retained by tacking along the upper edge until perfectly dry, when the pattern represented in Fig. 1 will have assumed the form shown in Figs. 4 and 7, having the appearance somewhat of a low-cut slipper with a Scotch sole. When perfectly dry and hard, 90 the heel part or counter is permanently se- 95

100

cured in position by a vertical row of stitching, as at *g*, engaging the laps of the bevel-edges *a'*, *b'*, *c'*, and *a*.

The combined sole, welt, and counter having now been produced, the next step in the manufacture of a boot or shoe, according to my invention, is to unite the outsole, if there be such, and upper to said combined sole, welt, and counter, and to do which I proceed as follows: An upper, be it either for a boot or shoe, is first lasted in the ordinary manner, as shown in Fig. 8—that is to say, a thin lining, *i*, corresponding in shape to the sole of the last, is first placed upon the bottom of the last *L*. The upper *u*, having the usual thin lining, *l*, secured therein, is now placed upon the last and its edges drawn down over said last and secured by tacks *t*. After the upper has been lasted, the tacks *t* are carefully withdrawn, a few at a time, and the edges of the upturned back, as shown in Fig. 9, but with the lining still remaining in position upon the last. At the same time with this removal of the edges of the upper the lining, or it may be the inner thickness of a double upper when such is used, is secured in position by a few stitches extending through said lining and partially through the inner sole-lining, *i*, as shown at *s*, Fig. 9. After thus securing these parts, the sole-lining and side-lining, together, which also assists to retain the upper in its proper position upon the last, the combined sole, welt, and counter is now placed in position—that is, the edges of the upper being in the position shown in Fig. 9, the combined sole and welt is slipped over the same, as shown in dotted lines of Fig. 9—in which position the curved edges or boxing *e* of the combined sole, &c., will fit against the lining *l* and the sole part *A* against the sole-lining *i*, as shown in Fig. 10. The edges of the upper are now brought down over the curved edge *e* of the combined sole, &c., and secured by a row of obliquely-placed stitches, *h*, through said upper, close against the angle of the slot *d* and through the flange *f*, as shown in Figs. 10 and 13. A second row of vertically-placed stitching, *j*, is now placed along the outer edge of the upper and flange *f* of the combined sole, &c., when, after affixing the heel in the usual manner, the boot or shoe is complete—that is, for a single-sole boot or shoe. Should a double-sole boot or shoe be desired, as represented in Figs. 10 and 11, previous to the placing of the second row of stitches *j* the outsole *K* is applied in position and secured by the stitching *j*, which in this instance passes directly through both the edges of the upper, combined sole and welt, and outsole, as shown in Fig. 13. Among the many advantages of a boot or shoe when constructed as herein shown and described is that there is no direct communication by nail, peg, or thread from the outside of the outsole to the inside of the insole, so that the entrance of dust or water occurring through said nail-holes or broken stitching is

prevented; and, because of the intervening strip, *e*, formed integral with the sole, being made to extend upward around the toe and sides of the foot, said portion of the boot or shoe is strengthened and rendered water-proof, for water to effect an entrance must first pass beneath two rows of stitching, then upward about half-way of the height of the upper, between said upper and the edge *e* of the combined sole, &c., then down said edge between it and the lining, then beneath the sole-lining, and around the same to the foot.

A strong serviceable boot or shoe is the result of this construction and arrangement of the parts, and the part that usually first breaks and becomes leaky—viz., the juncture of the sole and upper—is in this instance the strongest and less liable to break than other portions, and numerous soles may be applied as fast as one is worn out, or so long as the flange *f* will bear the stitching, which flange takes the place of the welt usually employed. The curved edges *e* of the combined sole, &c., being of stiff sole-leather and molded to the form of the foot, the foot, while it is held secure in its proper place within the boot or shoe, is permitted to assume its proper natural position, and is neither cramped nor crowded. Owing to the V-cuts and beveled edges thereof in the counter, said counter is caused to assume a curved form, as shown in Fig. 6, whereby the said counter closely embraces and clasps the heel, after the same is once in position in the boot or shoe, so that the slipping up and down of the heel is prevented.

Having thus described my invention, what I claim as new therein, and desire to secure by Letters Patent of the United States, is as follows, viz:

1. In a boot or shoe, the sole *A A' A''*, having the V-spaces at the heel portion formed with beveled edges which lap upon each other, and the groove or slit *d*, to form the two separate flanges *f* and *e* around the foot portion, the one, *e*, being beveled, for the purposes specified.

2. In a boot or shoe, the combined sole, welt, and counter formed of a single piece of sole-leather, with the curved edge *e*, to form the boxing or end and sides of the boot or shoe, straight flange *f*, to form the edge of the sole, and pieces *a b c A''*, having bevel-edges integral with the sole to form the counter, substantially as described, for the purposes specified.

3. A boot or shoe formed of an upper with the usual lining therein, a thin sole-lining, a combined sole, welt, and counter formed with curved sides, and end *e*, and sole-flange *f*, interposed between said upper and lining and secured in position by stitches passing obliquely through the edge of the upper and flange *f* of the sole, and an outer or second sole also secured in position by a row of stitches passing vertically through the edge of said second sole, first sole, and upper, substantially as described, for the purposes specified.

4. As an improved article of manufacture, a sole for boots and shoes constructed with a wide beveled edge, *e*, made to extend up the sides to form the boxing around the end and sides of the boot or shoe, a kerf, *d*, and narrow flange *f*, extending outward at right angles to the part *e*, and to which the upper is secured and counterformed integral therewith, substantially as described, for the purposes specified.

5. The combination, in a boot or shoe, of the sole having a wide bevel-edge, *e*, to form the

boxing around the sides and end thereof, a kerf, *d*, and a narrow flange, *f*, at right angles to the part *e*, and upper *u*, secured to said flange *f* upon the outside of the boot or shoe, 15 substantially as described, for the purposes specified.

BENJ. A. PILLOW.
